UNITED STATES PATENT OFFICE.

ROY T. AXE, OF SYRACUSE, NEW YORK, ASSIGNOR TO THE O. M. EDWARDS COMPANY, INC., OF SYRACUSE, NEW YORK, A CORPORATION OF NEW YORK.

WINDOW-SASH CONSTRUCTION.

Application filed September 11, 1925. Serial No. 55,765.

This invention relates to sheet metal window sashes and has for its object a particularly simple and efficient means within the sash for engaging the window guide and holding the sash from undue lateral shifting.

The invention consists in the novel features and in the combinations and constructions hereinafter set forth and claimed.

In describing this invention, reference is had to the accompanying drawings in which like characters designate corresponding parts in all the views.

Figure 1 is a fragmentary elevation of a window sash embodying my invention, the window guide being shown and a portion of the sash being broken away to show the coaction of the guide with the sash.

Figure 2 is a fragmentary edge view thereof.

Figure 3 is a sectional view on line 3—3, Figure 1.

This sash comprises sheet metal stiles or stiles bent up from sheet metal U shaped in general form or in the form of a channel open at its outer edge, the intermediate portion of the U shaped formation being formed to receive the margin of the glass pane, window guides extending into the stiles through the open outer edges thereof and means within the stiles for engaging the edge faces of the guides to prevent the sash from lateral shifting and also relieve the thin, front and rear walls or flanges of the stiles from the side thrust of the sash.

1, 2 and 3 designate respectively the stiles and the lower and upper rail of the sash which are usually all formed hollow and of sheet metal, although in so far as this invention is concerned, the stiles only may be formed of sheet metal, or rather the members of the sash which engage the window guides during sliding of the sash whether the sash slides horizontally or vertically. Preferably, the stiles and rails are of the same general construction and are formed up of thin, light sheet metal and are U shaped in general form in cross section. This is so with the exception of the top rail but the difference is of no consequence in so far as this invention is concerned.

Each stile 1 is formed so as to have opposing side walls or side flanges 4 which are connected along the inner edge of the stile by an intermediate portion 5 formed with a

re-entrant groove 6 for receiving the margin of the glass pane. The stile is open at its edge for receiving a projecting guide rib 7 on the window frame. In order to relieve the thin edges of the opposing walls or flanges of the stile from side thrust owing to the engagement thereof with the window frame, the stile is provided with metal inserts which ride upon the edge face of the guide, the side wall of flanges of the stile 65 projecting beyond the outer face of the inserts. These inserts are generally like arms of L shaped corner irons 8, there being a corner iron at each corner and the outer surface of these corner irons are disposed 70 midway between the outer and inner edges of the stile. Hence, a groove is formed about one-half the depth of the stile, for receiving the window guide.

The corner irons are located only at the 75 corners and the greater part of each stile between the corner iron does not have any bearing on the window guide.

In other words, the sash bears against the guides only at its corners. In window 80 sashes, the sash members are connected either by a miter joint or by a square joint.

In the sash here illustrated, each stile is interposed between the ends of the lower and upper rails 2, 3, that is, the ends of the rails lap the ends of the stiles and the end portions of the sides of the top and bottom rails form flanges 9 which together with a portion of the corner iron confine a groove or passage at 10 which forms a continuation 90 of the guide receiving passage or grooves of the stile.

Obviously, in operation, the upright portions of the corner irons will engage the window guide and relieve the walls of the 95 stiles from side thrusts.

The construction of the sash lock shown herein forms no part of this invention, but forms the subject matter of my application Sr. No. 43558, filed July 14, 1925. 100

What I claim is:

1. A window sash comprising stiles formed of sheet metal, each stile being U shaped in cross section with the intermediate part of the U shaped formation formed with a re-entrant groove for receiving the margin of the glass pane, the stile being open at its outer edge, inserts arranged in the stile, the opposite walls of the stile extending beyond the outer faces of the inserts and a 110

- window guide extending between the opposite walls of each stile, the outer faces of the inserts sliding on the edge face of the guide.
5. 2. A window sash comprising sheet metal stiles and rails being hollow and each stile being U shaped in general form and being open at its outer edge, corner irons arranged within the stiles and the rails at each corner,
- 10 the side walls of each stile extending beyond the outer edge faces of the corner iron, forming the bottoms of passages for receiving the window guide and the ends of the rails being formed with passages constituting continuations of the passage of the stile, and window guides extending into such passages, the outer faces of the portions of the corner irons located in the stiles, engaging the edge faces of such guides.
- 15 3. A window sash construction comprising thin sheet metal hollow stiles, each stile being U shaped in general form and open at its outer edge, a guide coating with each stile, the guide and stile being so arranged that one embraces the other and the guide stiffens the stile and means between the opposing walls of the stile having running engagement with the guide for receiving the side thrusts of the sash and relieving the opposing walls of the sheet metal stile from the side thrusts.
- 20 4. The window sash construction of claim 3 in which the means within the stile having running engagement with the guide is spaced apart lengthwise of the stile.
- 25 5. A window sash construction comprising thin, hollow, sheet metal stiles, each stile being open in the form of a channel open at its outer edge and formed with means at its inner edge for receiving the margin of the
- pane, the stile having inserts at the bottom of the channel, and means for guiding the sash and stiffening each stile, the latter means projecting into the stile through the outer open edge thereof and slidably engaging the walls of the stile and the inserts.
- 30 6. The window sash of claim 5 in which the inserts are spaced apart lengthwise of the stile.
- 35 7. The window sash construction of the claim 5 in which the inserts are arranged at the corners of the sash.
- 40 8. A window sash construction comprising a thin, sheet metal stile open at its outer edge and shaped at its inner edge to hold the margin of the glass pane, the stile being U-shaped in general form, inclosing a channel open at the edge of the stile, and means for stiffening the sheet metal stile, and for holding and guiding the sash, said means projecting into the stile through the open edge thereof to near the bottom of the channel confined by the stile, said means slidably fitting the front and rear walls of the stile.
- 45 9. The window sash of claim 8 in which each stile is provided with inserts at the bottom of the channel providing runners for engaging said stiffening and guiding means.
- 50 10. The window construction of claim 3 in which the means within the stile comprises inserts at the corners of the stile, said inserts being spaced apart so that there is a space extending lengthwise of the stile between the inserts, the inserts having running engagement with the guide.
- 55 70 75 In testimony whereof, I have hereunto signed my name, at Syracuse, in the county of Onondaga, and State of New York, this 3rd day of September, 1925.
- ROY T. AXE.
